US0D1078096S

(12) **United States Design Patent** (10) **Patent No.:** **US D1,078,096 S**
(45) **Date of Patent:** **** Jun. 3, 2025**

(54) **STEPPING STONE**

(71) Applicant: **Delu Meng**, Tai'an (CN)

(72) Inventor: **Delu Meng**, Tai'an (CN)

(**) Term: **15 Years**

(21) Appl. No.: **29/990,568**

(22) Filed: **Feb. 21, 2025**

(51) **LOC (15) Cl.** **21-01**

(52) **U.S. Cl.**

USPC **D21/399**; D21/471

(58) **Field of Classification Search**

USPC D21/398, 399, 414, 415, 419, 421, 468, D21/471, 475, 576, 603

CPC A63H 3/50; A63H 33/10; A63H 33/32; A63B 9/00; A63B 26/003; A63F 9/00

(57) **CLAIM**

The ornamental design for a stepping stone, as shown and described.

DESCRIPTION

FIG. 1 is a front, right and top perspective view of a stepping stone, showing my new design;
FIG. 2 is a rear, left and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof; and,
FIG. 9 is an exploded perspective view of a stepping stone. The broken lines depict portions of the 'stepping stone' that form no part of the claimed design.

1 Claim, 9 Drawing Sheets
